BATTERY TERMINAL CONNECTER

Russell E. Rowe, Hyattsville, Md.

Application March 9, 1937, Serial No. 129,928

4 Claims. (Cl. 173—259)

This invention relates to electrical connecters, and more particularly to terminal connecters for storage batteries such as are commonly employed on automobiles.

5 What may be called the "standard" connecter most generally used comprises a split sleeve or tube adapted to receive the battery cable, and into which the end of such cable is soldered or "sweated".

10 Owing to the time required to perform this "sweating" operation, and to the fact that, in carrying it out when a new terminal connecter is to be applied, it is necessary to remove the entire cable from the car, numerous attempts

15 have heretofore been made to devise clamping means which may be employed to attach the terminal to the cable, so as to obviate the necessity of using solder. These may be designated as "clamp type" connecters.

20 Regardless of the efficiency or practicability of these clamp type connecters, their use gives rise to a commercially objectionable situation, in that it is necessary for a repair man to carry a complete stock of parts for both types of connecters, 25 in order to serve customers who may prefer one type or the other.

The general object of the present invention is to avoid this difficulty, and to this end I have devised improved clamping means which are 30 applicable to the standard solder type of connecter, without change. Thus it is necessary for a repair man to stock only this one standard type of connecter, and this may be used either in the ordinary way, for those who desire a soldered job, or, by employing my improved additional parts, as a clamp type connecter, for those who prefer the clamp type. My improved clamping means may therefore be regarded as in the 35 nature of an "adapter", serving to change the standard solder type connecter into a clamp type, when desired.

A further object of the invention is to provide 40 an adapter or attachment of the kind above described, which shall be simple and cheap in construction, efficient in operation, and easy to assemble and apply.

45 With the above and other objects in view, the invention consists in the construction and arrangement of parts hereinafter described and claimed and illustrated in the accompanying drawing, in which:—

50 Fig. 1 is a plan view showing my improved adapter assembled with a standard terminal connecter and cable;

Fig. 2 is a transverse section on the line 2—2 of Fig. 1;

Fig. 3 is a longitudinal or horizontal section through the assembly shown in Fig. 1;

Fig. 4 is a view similar to Fig. 2 but showing a 5 slightly modified construction;

Fig. 5 is a perspective view of the block forming the principal part of my improved adapter;

Fig. 6 is a perspective view of one of the bands or hoops which I employ; 10

Fig. 7 is a perspective view of a compression plate used in connection with my improved clamping means;

Fig. 7a is an inside view of said plate; and

Fig. 8 is a perspective view of the standard 15 form of terminal connecter herein referred to.

Referring to the drawing in detail, and more particularly first to Fig. 8, the so-called standard terminal connecter comprises a split ring or clamp 1, adapted to engage a battery post, the ends 20 of the clamp being drawn together by means of a bolt 2 having a nut 3.

Carried by the side of the clamp 1 opposite the bolt 2 is a cylindrical split sleeve or tube 4, adapted to receive the end of a cable, and provided with a longitudinal slot or opening 4a, having spaced edges 4b.

My improved adapter comprises a block 5, best shown in Fig. 5, such block preferably having a concave inner surface 5a. The side edges of 30 the block are extended, as at 6, to provide portions which engage the inner surface of the sleeve 4, as clearly shown in Fig. 2, and adjacent the outer surface of each of the portions 6 is a longitudinally extending shoulder 7, the shoulders 35 1 being spaced apart a distance substantially equal to the width of the slot 4a.

Overhanging the portions 6 at each side of the block, and spaced therefrom by the shoulders 7, is a flange 8, and by reference to Fig. 2 it will 40 be clear that the portions 6, together with the shoulders 7 and flanges 8, form longitudinally extending grooves which are adapted to fit over the edges 4b of the sleeve adjacent the slot. 45

A clamping screw 11 passes through and is threaded in an opening 9 in the block 5, this screw being disposed radially of the sleeve 4. The inner end of the screw engages a clamping plate 12, preferably of arcuate form, having transverse 50 ribs 12a on its inner side, which clamping plate bears against the end of the cable B. In the drawing, the battery post is designated by the numeral A.

The ends of the block 5 are preferably notched 55

or cut away, as indicated at 10, in order to provide seats for a pair of bands or hoops 13.

In practice, when it is desired to employ my improved adapter, instead of sweating the cable 5 end into the sleeve 4, I slide the block longitudinally into the slot or opening 4^a of the sleeve, with the grooves at the sides thereof engaging the edges 4^a of the sleeve. I then place over the ends of the sleeve and block the bands or 10 hoops 13, as clearly shown in Fig. 1, these bands making a snug fit. I then insert the cable end in the sleeve, preferably with the plate 12 in position thereon, and then turn up the screw 11 so that its end bears firmly against the plate 12, as 15 shown in Fig. 2. The cable end is compressed between the plate 12 and the opposite wall of the sleeve and tightly and securely clamped therein. It will also be observed that the area of electrical contact is relatively large, the stranded 20 cable being somewhat flattened or deformed, and pressed firmly against the inner surface of the sleeve.

Another feature of the invention is also shown in Figs. 1 and 2. This consists of a set screw 25 14 which is threaded into the terminal or clamp 1 and disposed at an angle to the axis thereof, so that when this screw is turned up, its inner end bites into the post A and thus assists in locking the clamp in position, as well as in establishing a good electrical contact. This screw 30 may or may not be used in connection with the other features of the invention, and therefore is not illustrated in Figs. 4 and 8.

In Fig. 4, I have illustrated a slightly modified 35 arrangement in which the cable end, instead of being compressed against the inner wall of the sleeve, is compressed against the inner surface of the block 5 itself. In this modification, there is employed a clamping screw 15, having an 40 elongated concave head 16 at its inner end for engaging the cable. The screw passes freely through an opening in the block 5 and the nut 17 is threaded on the outer end thereof. It will

be understood that in this modification the screw 15 passes through the stranded cable itself, it being necessary to open or spread the strands apart in order to insert the screw.

What I claim is:

1. The combination with a battery terminal comprising a post clamp rigidly carrying the usual split sleeve connector having a longitudinal slot, of a block fitting between the edges of said slot and having a portion engaging the inner 10 surface of said sleeve adjacent each side of said slot, and a clamping screw passing through said block radially of said sleeve.

2. The combination with a battery terminal comprising a post clamp rigidly carrying the usual 15 split sleeve connector having a longitudinal slot, of a block having grooves in its sides slidable lengthwise over the edges of said slot, and lying partly within said sleeve, said block filling said slot, and a clamping screw passing through 20 said block and terminating inside of said sleeve.

3. The combination with a battery terminal comprising a post clamp rigid with the usual split sleeve connector having a longitudinal slot, of a block interlocked with the edges of said slot 25 and having a portion engaging the inner surface of said sleeve adjacent each side of said slot, binding means for preventing said sleeve from expanding, and a clamping screw passing through said block.

4. The combination with a battery terminal comprising a post clamp rigid with the usual cylindrical split sleeve connector having a longitudinal slot, of a block having a portion filling 30 said slot and flush with the outer surface of said sleeve, and having another portion engaging the inner surface of said sleeve adjacent the edges of said slot, a pair of bands encircling said sleeve and the flush portion of said block, and a clamping screw passing through said block 40 at a point between said bands.

RUSSELL E. ROWE.
